Primary Examiner — Elizabeth A. Albert*(74) Attorney, Agent, or Firm* — Eric E. Silverman(57) **CLAIM**

The ornamental design for a dispenser, as shown and described.

DESCRIPTION

FIG. 1 is a perspective view showing a new design for a dispenser;

FIG. 2 is a front view thereof, a rear view being a mirror image thereof;

FIG. 3 is a left side view thereof, a right side view being a mirror image thereof;

FIG. 4 is a top view thereof;

FIG. 5 is a bottom view thereof; and,

FIG. 6 is a perspective view thereof showing the Dispenser with a note.

The portions of the dispenser in FIGS. 1-6 shown in broken lines are included to show features that form no part of the claimed design.

1 Claim, 6 Drawing Sheets(56)
